UNITED STATES PATENT OFFICE.

JOSEPH PLATT, OF DETROIT, MICHIGAN.

BANK-PROTECTING DEVICE.

Application filed January 29, 1926. Serial No. 84,686.

My invention relates to bank protecting devices and an object of my improvements is to provide a deal tray that shall fully protect the teller while facilitating the handling of money.

I accomplish this object in the device shown in the accompanying drawings, in which:

Figure 1 is an isometric view of a deal tray embodying my invention and so much of a bullet proof partition as is necessary to illustrate its connection therewith.

Figure 2 is a cross section of the same.

Figure 3 is a side elevation of the tray.

Figure 4 is a plan view of a portion of one end of said tray.

Figure 5 is an inverted plan view of the other end of said tray, and

Figure 6 an elevation, looking as from the right of Figures 1 and 2 and showing a portion of the counter and adjacent parts.

K is the counter. L and N are bullet proof panels at the side of the tray. B is a metal cross bar parallel to and a little above the upper surface of the counter and A is a bullet proof sheet of glass resting upon the cross bar B and filling the space between said panels.

C is a metal bar secured at the under side of the bar B, extending downward toward the counter and across the opening between the panels L and N, except for the sides of the tray, at each end. The bar C may be hollow as indicated at H.

The deal tray is located upon the counter K, the bar C extending downward therein between its outer and inner edges.

The body of the tray is made of soft steel, and is provided with sides and an elevated ridge G at its front edge extending between its sides at a convenient distance in front of the partition A and bar C. The upper edge of the ridge G comes at about the level of the lower edge of the bar C. F is a second ridge extending upward and between the sides of the tray, parallel to the ridge G and a short distance back of the partition A and bar C. This leaves a flat portion D of the bottom of the tray partly in front of the bar C and partition A.

Back of the ridge F the bottom of the tray extends horizontally backward for a short distance until it rises slanting backward to the elevated horizontal plane surface J at the rear of the tray. The surface J is at a level

considerably above the lower edge of the bar C.

The ridge F divides the bottom of the tray into two parts, respectively, directly accessible to the customer and teller into which bills, papers and pass books may be laid. The customer may place articles flat-wise in the outer part D and shove them to the rear of said part where they can be reached by the teller.

The teller may place such articles in the tray back of the ridge F where they cannot be reached by the customer.

E is a bullet proof sheet of steel secured at its edges at V and W below the bottom of the tray, leaving a space between said sheet and the bottom of the tray.

The bottom of the tray may be penetrated by a bullet but it will largely stop the same and the plate E will completely stop it so that the bullet will remain in the space between said sheet and bottom of the tray.

By this arrangement the handling of the money, papers and pass book may proceed in the usual way and a weapon cannot be brought into position to hold up the teller, nor can bullets be fired to reach a victim by glancing from the bottom of the tray.

The ridge F may be omitted if the lower edge of the bar C is brought much lower but the construction is not as efficient and desirable.

What I claim is:

1. In an apparatus of the kind described, the combination of a bullet proof partition, a tray extending under said partition having an elevated outer and inner edge, the lower edge of said partition crossing said tray below, or approximately in, a plane extending between the upper portions of said edges at a distance from said outer and inner edges sufficient to permit the usual articles to be placed in said tray, said tray being made of a material that permits the penetration of a bullet, and a bullet proof shield located under said tray so as to catch and retain any bullet that may penetrate said tray, said tray being so located as to prevent a bullet from glancing from said shield.

2. In an apparatus of the kind described, the combination of a bullet proof partition, a tray extending under said partition having an elevated outer and inner edge, the lower edge of said partition crossing said

tray below, or approximately in, a plane extending between the upper portions of said edges at a distance from said outer and inner edges sufficient to permit the usual articles to be placed in said tray, said tray being provided with a ridge F extending upwardly from its bottom a short distance back of said partition for the purpose described.

3. In an apparatus of the kind described, the combination of a bullet proof partition, a tray extending under said partition having an elevated outer and inner edge, the lower edge of said partition crossing said tray below, or approximately in, a plane extending between the upper portions of said edges at a distance from said outer and inner edges sufficient to permit the usual articles to be placed in said tray, said tray being provided with a ridge F extending upwardly from its bottom a short distance back of said partition, said tray being made of a material that permits the penetration of a bullet, and a bullet proof shield located under said tray so as to catch and retain

any bullet that may penetrate said tray, said tray being so located as to prevent a bullet from glancing from said shield.

4. In an apparatus of the kind described, the combination of a bullet proof partition, a tray extending under and filling the space beneath said partition, said tray being provided with an upwardly extending ridge G spaced horizontally from said partition and in front thereof for the purpose described, an upwardly extending ridge F a short distance behind said partition, the bottom of said tray rising to an elevated portion J at its rear, said tray being of a material that may be penetrated by a bullet and a shield E unpenetrable by a bullet, and located below said tray so as to catch and retain any bullet that may penetrate said tray, said tray being so located as to prevent a bullet from glancing from said shield, said partition crossing said tray below, or approximately in, a plane extending between the upper portions of said edges.

JOSEPH PLATT.
